DESIGN FOR A COMBINATION FRAME AND SUPPORT

Ernest C. Shallor, Detroit, Mich.

Application April 2, 1945, Serial No. 118,829

Term of patent 7 years

(Cl. D29—20)

To all whom it may concern:

Be it known that I, Ernest C. Shallor, a citizen of the United States of America, residing at Detroit, in the county of Wayne and State of Michigan, have invented a new, original, and ornamental Design for a Combination Frame and Support, of which the following is a specification, reference being had therein to the accompanying drawing, forming a part thereof, wherein:

I claim:

The ornamental design for a combination frame and support, substantially as shown.

ERNEST C. SHAILOR.
